UNITED STATES PATENT OFFICE.

RAY H. MANSON, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

MICROPHONE.

1,378,708.

Specification of Letters Patent.

Patented May 17, 1921.

Application filed June 23, 1917. Serial No. 176,512.

To all whom it may concern:

Be it known that I, RAY H. MANSON, a citizen of the United States of America, residing at Rochester, in the county of Monroe and State of New York, have invented certain new and useful Improvements in Microphones, of which the following is a full, clear, concise, and exact description.

This invention relates to telephonic devices and more particularly to a microphonic device in which the resistance varying medium is comminuted material retained between two contact elements constituting walls of a containing chamber, one of 10 the contact elements being fixed and the other movable relative to the first.

It relates particularly to providing in such a containing chamber for the comminuted material an improved construction 20 whereby the resistance to the movement of the movable electrode is reduced to a minimum, and the effective area of this electrode having given resistance to movement is increased.

25 It is an object of my invention to provide the means for accomplishing the aforesaid objects without causing defective operation of the instrument in other respects, such as packing of a portion of the granules of comminuted material which may be granulated carbon.

Other objects of my invention and the invention itself will be better understood from the description which follows.

35 The drawing shows a section of a telephonic microphone element so constructed as to constitute an embodiment of my invention. The drawing shows the telephonic element in section and in which 1 is the fixed carbon electrode, 2 is the movable carbon electrode, the fixed electrode being rigidly secured to the fixed shank 3 of the element which is adapted to be secured to the bridge 40 of a telephone transmitter in any of the well-known ways, and the movable electrode 2 is secured by a metallic mount 4, stem 5, and clamping nuts 6 and 7 to a diaphragm 8, a portion of which only is shown also in section. The comminuted granular carbon 9 is 45 also shown in the drawing between the electrodes 1 and 2. The main diaphragm 8 will be constructed of some suitable material,

such as aluminum, and an auxiliary sub-diaphragm 10 is provided; and as illustrated in the drawing is constructed of a 55 thin piece of sheet mica.

The movable electrode 2 is by its mount 4 clamped securely and peripherally to the mica sub-diaphragm 10 by a metallic disk member 11. The mount 4 which is in the 60 form of a disk has its edge 12 beveled so that the face 17 of the electrode, 2, is of larger area than the face 14 of the mount. The carbon electrode 2 mounted on the beveled disk 4 is in the preferred embodiment illustrated, of the same diameter as the larger face 13 of the mount 4 to which it is 65 preferably secured. The clamping disk 11 is preferably of the same diameter as the smaller face 14 of the mount 4. 70

In prior constructions it has been usual to have the diameter of the movable electrode 2, both faces of the mount 12 and the clamping disk 11, of the same diameter. In my improved microphone I depart from this 75 custom and thereby attain a highly improved result as will be later described.

Again referring to the drawing constituting a part of this specification, the periphery of the mica sub-diaphragm 10 is securely 80 clamped by members 15 and 16, the member 15 also constituting a circular wall for the cup element. The shank 3 has an enlarged portion 18 constituting the outer wall of the cup, and to this outer wall is secured the 85 member 16 which in turn clamps the mica sub-diaphragm 10, the member 15 and the electrode 1 securely together so as to make all of these parts rigid with respect one to the other. The mica sub-diaphragm 10 has 90 a free portion where it may be flexed by the forward and backward excursions of the electrode 2 under the control of the vibrating diaphragm 8 when the transmitter of which the diaphragm is a part is operated. 95

It can be easily seen that if a microphone were to be built having the members 4 and 11 of the same diameter as the movable electrode 17, that this free portion of the mica sub-diaphragm 10 would be considerably 100 limited as it is limited with present constructions; and the resistance to flexure thereof greatly increased. It is important to have the electrode 2 of such a diameter as

will provide a large area on its face 17 to make contacts with the granules 9, and it is also very advantageous to decrease the resistance to flexure of the mica sub-diaphragm 10.

In the microphone of my invention I attain both of these advantageous results. It has previously been attempted to obtain the aforesaid results by a construction in which 10 the mount member corresponding to 4 was cut away so that the face such as 14, was of smaller diameter than the face upon which the electrode rests as 13, but the advantage of my improved construction was not secured 15 because the carbon granules would get between the enlarged portion of the mount and the flexible sub-diaphragm restricting its free movement. In the microphone of my invention I prevent the granules from 20 being secured between the mount and the sub-diaphragm by beveling the mount and giving the beveled edge a smooth surface.

What I claim is:—

1. In a microphone, the combination with 25 a granular carbon containing cup, a cylindrical inner wall therefor, a carbon electrode disk for one of the end walls thereof, a movable electrode, a disk mount for the said electrode having a beveled edge, the 30 said beveled edge causing the said mount to have its faces of different diameters, and a flexible diaphragm for the said microphone clamped to the smaller face of the said electrode mount, said flexible diaphragm with its carrying mount electrode disk forming the other end wall of the said containing cup.

2. In a telephone transmitter, the combination with a movable electrode and a 40 fixed electrode arranged in a containing chamber having a cylindrical wall, granulated carbon in the said containing chamber arranged to contact with opposing faces of the said electrodes, a beveled edge for 45 the movable electrode between its faces to cause one of the said faces to be of smaller diameter than the other, and a flexible wall for the said chamber to which the said movable electrode is clamped by its smaller face.

50 3: In a microphone, the combination with a containing chamber therefor having a cylindrical inner wall, a flexible diaphragm therefor, a movably mounted electrode secured thereto and adapted to be moved 55 thereby, a quantity of comminuted resistance material adapted to contact with a face of the said mounted electrode, the other face being secured to the said flexible diaphragm, the said mounted electrode having 60 its sides tapered, the first named face being larger than the second named face, and means to clamp the said flexible diaphragm over an end of the said chamber to close at one end of the said chamber.

65 4. In a microphone, the combination with

a containing cup therefor having a cylindrical inner wall, a flexible diaphragm, an electrode adapted to be moved thereby, a tapered mount for the said electrode to secure the said electrode to the said flexible 70 diaphragm, comminuted resistance material adapted to contact with one face of the said electrode, the other face being secured to the larger face of the tapered electrode mount.

75 5. In a microphone, the combination with a containing cup therefor having a cylindrical inner wall, a flexible diaphragm, an electrode, a mount engaging one face of the said electrode to secure it to the said flexible 80 diaphragm, comminuted resistance material adapted to contact with another face of said electrode, the said mount constituting a frustum of a cone, the inside diameter of the containing cup being substantially 85 greater than the diameter of the smaller end of the said mount, and means to secure the said smaller end of the said mount to the said flexible diaphragm, whereby the said mount may convey phonic vibrations 90 of the said diaphragm to the said electrode face.

95 6. In a microphone, the combination with a containing cup, a movable electrode therefor, a disk mount for said electrode having a beveled edge, said beveled edge causing the said mount to have faces of different diameter, a flexible diaphragm for the said microphone clamped to the smaller face of the said electrode mount, the said flexible 100 diaphragm, the said mount and the said electrode serving as an end wall of the said containing cup, another end wall and a substantially cylindrical side wall for the said containing cup, the diameter of the said electrode being greater than the diameter of the smaller face of the said electrode mount, and being less than the diameter of the flexible portion of the said flexible diaphragm.

110 7. In a telephone transmitter, the combination with a main diaphragm, an auxiliary diaphragm rigidly connected thereto, a containing chamber associated therewith, having parallel side walls, the said auxiliary 115 diaphragm forming a flexible wall of the said containing chamber, a movable electrode, a mount and a clamping member therefor to secure the said electrode to the said auxiliary diaphragm, the said mount forming the frustum of a solid, comminuted material adapted to contact with the said movable electrode and a fixed electrode also adapted to contact with the said comminuted material whereby the comminuted material is adapted to be compressed by movements of the diaphragm between the said electrodes.

120 8. In a microphone, the combination with a containing cup therefor having a cylindri- 130

- cal inner wall, a flexible diaphragm, a mounted electrode having a large and a small face, comminuted resistance material adapted to contact with the said large face, 5 the said mounted electrode being secured to the said flexible diaphragm by the said smaller face, the edges of the mounted electrode being so shaped as to form the frustum of a cone.
- 10 9. In a microphone, a casing provided with parallel inner walls and having an open end, a flexible diaphragm clamped to said casing to form a closure therefor, an electrode, a beveled mount for said electrode 15 located in said casing and secured to said diaphragm, a second electrode coöperating with the first, and comminuted resistance material engaging the opposing faces of said electrodes.
10. In a microphone, a casing open at one end and having an internal thread, a member threaded to engage the threaded portion of said casing, a diaphragm forming with said member a closure for said casing, a beveled mount carried by said diaphragm, 20 means for causing said diaphragm to engage said member, two electrodes within said casing, one of which is secured to said beveled mount, and resistance material engaging said electrodes. 25
- In witness whereof, I hereunto subscribe my name this 22nd day of June, A. D. 1917. 30

RAY H. MANSON.
